Primary Examiner — Rhea Shields

CLAIM

The ornamental design for a D-shaped tube package, as shown.

DESCRIPTION

FIG. 1 is a perspective view showing my new design;
 FIG. 2 is a front elevational view thereof;
 FIG. 3 is a top elevational view thereof; and,
 FIG. 4 is a right side elevational view thereof, the left side being a mirror image.

1 Claim, 3 Drawing Sheets(56)
